UNITED STATES PATENT OFFICE.

AUGUST H. EBERHARDT, JR., OF BEDFORD, OHIO.

TICKET AND PROGRAM HOLDER.

Application filed November 8, 1926. Serial No. 147,128.

My invention relates to certain new and useful improvements in ticket and program holders; and it consists in the construction and combination of the part, as shown in the accompanying drawings and set forth in the following specification.

The object of my invention is to provide a ticket and program holder for theatres, railroad trains, busses and the like.

10 In the accompanying drawings, which illustrate my invention, Fig. 1 is a sectional view of a form of ticket and program holder. Fig. 2 is a plan view of Fig. 1 showing the top plate removed. Fig. 3 is a top view 15 of a top plate that goes with Fig. 2. Fig. 4 is a full side view of one form of casing, showing the top plate integral with the casing. Fig. 5 is a plan view of Fig. 4. The openings 11:11:11:11: provide means to 20 fasten the unit to place.

The plate 12 is a form of top plate, being rectangular in shape and is provided with an integral boss 18 that fits into the casing 13. The perforated leaf spring 14 is adapted to hold the ticket or program when inserted between the top plate and the spring, the top plate and leaf spring being held in the casing by the screw 16.

25 In the casing 15 the top plate and the boss 17 are integral with the casing, the boss 17 being provided with a threaded hole or bore to take the screw 16. The boss 18 is integral with the top plate 12 and is provided with a threaded hole or bore to take the 30 screw 16 that passes through the opening 16' in the diaphragm 6', in assembling this style of holder.

35 In one form the perforated leaf spring is inserted between the plate's integral boss and the integral diaphragm in the casing, the screw inserted and screwed to place, this method clamping the leaf spring between the boss and the diaphragm.

40 In the other form the casing, the top plate and boss are integral throughout, in this style the perforated spring is mounted in the casing against the boss and held in place by the screw, the screw passing through the perforation in the spring, and being screwed 45 to place in the boss in the casing.

What I claim as new, and desire to secure by Letters Patent, is—

50 1. In a ticket and program holder, the combination of a hollow casing having a top plate integrally connected thereto inter-

mediate the ends thereof and separated from the casing and forming therewith oppositely disposed receiving openings, a threaded bore in said top plate, a perforated leaf spring disposed in the casing and engaging the ends 55 of the casing and also the under side of the top plate at the receiving openings to hold the objects inserted therein, and means to fixedly secure the leaf spring to the top plate on its under side in the casing.

55 2. In a ticket and program holder, the combination of a hollow casing having a top plate integrally connected thereto by means of a boss intermediate the ends thereof and separated from the casing by said boss and forming therewith oppositely disposed receiving openings, a threaded bore in said boss, a perforated leaf spring disposed in the casing and mounted on the boss and engaging the ends of the casing and also the under side of the top plate at the receiving 60 openings to hold the objects inserted therein, and means to fixedly secure the leaf spring to the boss in the casing.

65 3. In a ticket and program holder, the combination of a hollow casing having a top plate integrally connected thereto by means of a boss intermediate the ends thereof and separated from the casing by said boss and forming therewith oppositely disposed receiving openings, a leaf spring disposed in the casing and mounted on the boss and engaging the ends of the casing and also the under side of the top plate at the receiving 70 openings to hold the objects inserted therein.

75 4. In a ticket and program holder, the combination of a hollow casing having a top plate connected thereto intermediate the ends thereof and separated from the casing and forming therewith oppositely disposed receiving openings, a leaf spring disposed in the casing and engaging the ends of the casing and also the under side of the top plate at the receiving 80 openings to hold the objects inserted therein.

85 5. In a ticket and program holder, the combination of a hollow casing having a top plate integrally connected thereto by means of a boss intermediate the ends thereof and separated from the casing and forming therewith oppositely disposed receiving openings, a threaded bore in said boss, a perforated leaf spring disposed in the casing and mounted on the boss and engaging the under side of the top plate at the receiving 90

openings to hold the objects inserted therein, and means to secure the leaf spring to the boss in the casing.

6. In a ticket and program holder, the combination of a hollow casing having a top plate integrally connected thereto and separated from the casing and forming therewith oppositely disposed receiving openings, a boss intermediate the ends of the casing and integral with the top plate, a leaf spring mounted on the boss and engaging the under side of the top plate at the receiving openings to hold the objects inserted therein.

7. In a ticket and program holder, the combination of a hollow casing having a

top plate integrally connected thereto intermediate the ends thereof and separated from the casing and forming therewith oppositely disposed receiving openings, a perforated leaf spring disposed in the casing 20 and engaging the under side of the top plate at the receiving openings to hold the objects inserted therein, the top plate being provided with a threaded bore, and means to secure the leaf spring to the under side of 25 the top plate.

In testimony whereof I have hereunto subscribed my name.

AUGUST H. EBERHARDT, JR.
